RAILWAY CAR METAL DOOR

Harold H. Henricks, Youngstown, Ohio, assignor
to The Youngstown Steel Door Company,
Cleveland, Ohio, a Corporation of Ohio

Application March 5, 1931. Serial No. 520,249

10 Claims. (Cl. 189—46)

This invention relates to improvements in railway car metal doors and more particularly to improvements in the general type of sheet metal car side doors disclosed in U. S. McWilliams 5 Patent 1,742,408 of January 7, 1930.

In railway car side doors, of both single and double type, the doors are subjected to very rough handling in the opening and closing thereof. In the event of any part of the door catching against 10 or fouling the door post while being moved, it frequently happens that the operators use crow-bars or sledges to force the movement of the doors, with the result that parts are broken off or distorted, rendering the operation of the doors still 15 more difficult thereafter and ultimately necessitating major repairs. For weather and spark sealing purposes, and also to prevent theft, it is highly desirable that the inner surfaces of the doors around all edges thereof be maintained as 20 close as possible to the members defining the door openings when the doors are in closed position. In prior types of metal doors where reinforcing plates or strips have been employed on the inner side thereof, considerable difficulty has been experienced because of the reinforcing plates or 25 strips along the inner surfaces of the vertical edges of the door fouling against the door posts, due to the fact that the inner edges of said strips are disposed in a plane inwardly of the plane of 30 the other parts of the door, which serve to guide the door in its sliding movements.

One object of my invention is to provide a slideable metal door, especially adapted for railway cars, comprised mainly of sheet metal so formed 35 that all inside marginal portions of the sheet metal have their inner surfaces lying in a common plane, the inner surfaces of the door within said marginal portions being free from any projections or shoulders extending inwardly of said 40 plane, whereby to avoid any possible fouling with the door posts during operation of the door to open and closed positions.

Another object of my invention is to provide 45 a slideable sheet metal door having vertical, strengthening corrugations along its front and rear vertical edges with flat marginal portions outwardly thereof and bracing or bridging strips covering said corrugations secured to the main sheet metal portions along the opposite sides of 50 the corrugations, the inner vertical edges of said strips or plates being offset laterally outward so as to avoid any laterally, inwardly projecting edges or shoulders that might otherwise catch against any of the stationary car parts when the 55 door is being opened and closed.

Another object of my invention is to provide a sheet metal door having bracing plates or strips along its top, bottom and vertical edges on the inner side thereof, wherein said top and bottom plates serve to guide the door on its inner 60 surface and wherein all other portions of the side plates or strips and door proper are disposed either flush with or laterally outwardly below the plane of said top and bottom plates to thereby eliminate any possible interference or fouling with 65 the door post or other fixed car parts during movements of the door.

A still further object of my invention is to provide a sheet metal door having edge reinforcing plates or strips along the top, bottom and vertical 70 edges on the inner surface thereof, wherein the marginal portions of said plates or strips all lie in a common plane, limiting the lateral inward movement of the door with reference to the fixed car structure, all other parts of the door proper 75 and plates within the area defined by said marginal portions lying in a plane laterally outwardly offset so as to avoid bearing thereof against the door posts during closing and opening movements 80 of the door.

Other objects of the invention will more clearly appear from the description and claims herein-after following.

In the drawings, forming a part of this specification, Figure 1 is a side, elevational view of a 85 portion of a box car, showing my improvements incorporated in a single side door thereon. Figure 2 is a horizontal, sectional view, upon an enlarged scale, corresponding to the section line 2—2 of Figure 1, parts being broken away to better 90 accommodate the figure on the sheet. Figure 3 is a broken, vertical, sectional view upon an enlarged scale, corresponding to the section line 3—3 of Figure 1. And Figure 4 is an interior, 95 elevational view upon an enlarged scale of one lower corner portion of the door showing my improvements more in detail.

In said drawings, the box car is shown as having a side door opening, defined by vertical Z-bar side posts 10 and 11 and threshold 12. The door 100 lintel may be of any desired construction and usually will comprise a Z-bar side plate 13 and suitable inner and outer retaining guide bars or strips 14. Associated with each of the door posts is a wood filler 15 and nailing strip 16, the fillers 105 preferably being protected by metal sheathing 17.

As customary, the front door post 11 has secured thereto a combined vertical stop and 110 weather spark sealing element 18, the latter preferably being in the form of an angle having its

outer flange 19 extending over but spaced from the corresponding post 11 so as to receive the front edge of the door therein. The rear door post is provided with a combined weather and 5 spark sealing strip 20 having a flange 21.

The door proper, as shown, preferably comprises three sheet metal panels A, B and C, arranged horizontally with their respective adjacent horizontal edges overlapped and riveted together, as indicated at 22 and 23. The three panels A, B and C together form a rectangular main door portion, which is preferably rigidified by integrally formed indentations or corrugations which, as shown, include vertically extending corrugations 24 and 25 adjacent each vertical edge, a horizontal, top corrugation 26 merging with and forming continuations of the vertical corrugations 24 and 25; a shortened bottom, horizontal corrugation 27 and a plurality of intermediate, horizontally extending corrugations 28-23, which merge at their ends with the vertical corrugations 24-25. All of said corrugations are extended laterally outwardly from the original main plane of the sheets. In the particular embodiment shown, the door is of the bottom hung type, for which purpose there are secured to the door near the two lower corners thereof roller-carrying brackets 29-29, having rollers 30-30 adapted to ride upon a track 31, secured at suitable intervals by brackets 32-32, to the usual channel side sill 33 of the car. Said track 31 has an outer depending flange 34 beneath and around which is disposed a hock-shaped section 35 depending from each roller bracket so as to 30 prevent outward movement of the lower portion of the door away from the car body. At its upper end, the door is provided with suitable brackets 36-36 cooperating with the retaining guide bars 14 to limit the outward movement of the 35 upper portion of the door.

The vertical edge corrugations 24-25 of the door proper are so located as to leave flat marginal portions 37 and 38 of the main sheet metal panels and corresponding flat marginal portions 45 will be left at the top and bottom horizontal edges of the door. At its front edge, the door is provided with a vertically extending bracing angle 39 secured to the door along the flat marginal portion 37, said angle 39 being adapted to 50 engage the front door stop 13 and form therewith a weather seal, said bar 39 having an outwardly inclined flange 40 disposed opposite the flange 19 when the door is in closed position as shown in Figure 2. At its rear edge, the door proper has secured thereto a vertically extending weather and spark sealing element 41, having a forwardly and inwardly inclined flange 42, cooperable with the flange 21 when the door is in closed position, as also clearly shown in Figure 2. To 55 further strengthen the rear vertical edge of the door and also to protect the sealing element 41, an angle 43 is preferably applied on the outer face of the marginal portion 38 and having one of its flanges extended laterally inwardly so as to 60 overlie the rear edges of the door panel sheets, bridging plate hereinafter referred to, and the sealing element 41. The vertical corrugations 24 and 25 may be interiorly braced by U-cross section elements 44-44 attached thereto by 65 rivets or otherwise.

In carrying out my invention, the door is provided on the inner surface thereof, with a top, horizontally extending reinforcing plate or bridging strip 45, a lower horizontal similar plate 46, as shown in elevation in Figure 4, and two

vertical, bridging plates or strips 47 and 48 covering the front and rear vertical edge corrugations 24 and 25, respectively.

Referring to Figure 4, it will be noted that the plate 46 bridges the lower horizontal corrugation 27 and extends the full width of the door, being secured to the main sheet metal panel C by horizontal series of rivets 49 and 50 above and below the corrugation 27. Said rivets are flush on their inner ends so as to avoid any protuberances or projections. Preferably also, the lower edge of the door is further strengthened by introducing an angle 51 between the extreme lower edges of said strip 46 and panel sheet C, as best illustrated in Figure 3, said angle 51 being notched out or cut away, as indicated at 52, to clear the rollers, as indicated. While Figure 4 illustrates the lower portion of the door, it will be understood that the arrangement is the same along the top edge of the door with respect to the reinforcing plate 45.

Each of the vertical bridging plates 47 and 48 extends between the two horizontal plates 45 and 46, as indicated best in Figure 4. Said plates are riveted by flush rivets to the inner surfaces 100 of the front and rear marginal portions 37 and 38, respectively, of the main door proper, as illustrated in Figure 2. Said outer marginal portions of each vertical bridging plate 47, as indicated at 53 in Figure 4, will lie in the same plane 105 as that of the top and bottom bracing plates 45 and 46 so that there is thus defined on the inner side of the door a common plane for all of the bracing plates horizontal and vertical.

Intermediate the extreme top and bottom ends 110 of the bridging or bracing plates 47 and 48, the panel sheets A, B and C between each of the horizontal corrugations 28, are laterally outwardly offset, as indicated at 54-54 best in Figure 2, for a short distance inwardly of each of the 115 vertical corrugations, the amount of said offsetting being at least equal to or preferably slightly greater than the thickness of the bracing plates 47 and 48. The bracing plates 47 and 48 then have their inner vertical edges secured to said outwardly offset portions 54-54 by a series of flush rivets 55-55, so that the inner vertical edges of each of the plates 47 and 48 intermediate their extreme top and bottom ends, are deflected outwardly or lie in a plane outwardly of the marginal plane, heretofore referred to, defined by the top and bottom bridging plates 45-46 and outer marginal portions 53 of the vertical plates 47 and 48. Near the extreme top and bottom ends of the plates 47 and 48, the latter will be sloped inwardly slightly, as indicated at 56 in Figure 4, to bring the extreme end portions of said vertical plates 47 and 48 in the same plane as the top and bottom vertical plates 45 and 46.

With the construction thus described, it will be observed that all portions of the door on the inner side thereof, within the marginal areas defined by the plates 45 and 46 and portions 53 of the vertical plates 47 and 48, lie in a plane slightly 140 laterally outwardly offset therefrom, thus eliminating any projections or shoulders that might otherwise interfere with the closing and opening movements of the door when sliding past the door posts. In this connection, it will be understood 145 that the lower plate 46 determines or limits the inward movement of the door with reference to the fixed car parts and the same is also true of the upper horizontal bracing plate 45, and hence serve as the guiding or positioning means for 150

- the door in its opening and closing movements, and it is, therefore, impossible for either inner vertical edge of the plates 47 or 48 to engage the door posts or for any central portion of the door panels proper to engage therewith. At the same time, it will be observed that the door is adapted to lie closely against the door posts when in closed position and during all opening and closing movements thereof, thus eliminating excessive spacing or clearance which would militate against proper sealing of the door against weather, sparks and theft when in closed position. 80
- I have herein shown and described what I now consider the preferred manner of carrying out the invention, but the same is illustrated only and all changes and modifications are contemplated that come within the scope of the claims appended hereto.
- I claim:
1. In a sliding door of the type having a main portion of sheet metal having outwardly disposed, integral, vertical corrugations near the edges thereof and flat marginal portions beyond the corrugations in the original plane of the sheet metal; bridging plates extending over said corrugations on the inner side of the door and secured to the sheet metal along the opposite sides of the corrugations, the main sheet metal portions, inwardly of the corrugations, being laterally outwardly offset where said plates are secured thereto, whereby the outer marginal vertical portions of said plates are disposed in a plane laterally inwardly of the plane of the inner vertical edges of said plates. 90
2. In a sliding door of the type having a main portion of sheet metal having laterally outwardly disposed, strengthened indentations therein, including vertical edge corrugations; horizontal top and bottom and vertical side reinforcing plates secured to the inner face of said main sheet metal portion, said top and bottom plates and the outer vertical edge marginal portions of said side plates all lying in a common plane constituting the inside guiding plane of the door, the inner vertical edge portions of said side plates and the central areas of the main sheet metal portion all lying in a plane laterally outwardly offset from said first mentioned plane. 105
3. In a sliding door of the type having a main portion of sheet metal having vertically extending edge corrugations and horizontal corrugations merging at their ends therewith, said main portion having flat margins around all edges outwardly of the corrugations and in the original plane of the sheet; horizontally extending top and bottom reinforcing plates on the inner side of said main portion; and vertical side plates on the inner side of said main portion, all of said plates being secured along their outer edges to said flat marginal portions of said main portion, the sheet metal of the main portion between said horizontal corrugations and inwardly of the vertical corrugations, being laterally outwardly offset at least the thickness of said plates and the vertical inner edges of said side plates being secured to said offset portions, whereby said top, bottom and outermost vertical edge portions of the side plates lie in a common plane, which is the innermost and inside guiding plane of the door. 120
4. In a sliding door of the type having a main portion of sheet metal having strengthening indentations therein; a reinforcing plate extending along the bottom edge of said main portion on the inner side thereof and secured thereto; and a reinforcing angle bar along the bottom edge of the door, said bar having one of its flanges disposed between and secured to the lowermost edge portions of said reinforcing plate and sheet metal comprising the main portion and its other flange extending outwardly below the bottom edge of said main portion. 130
5. In a sliding door of the type having a main portion of sheet metal having strengthening indentations therein, including vertically disposed corrugations adjacent the edges thereof; top and bottom reinforcing plates secured to the inner face of said main portion, said plates extending the full width of the door; and vertically disposed, side reinforcing plates secured to the inner face of said main portion, said side plates extending between said top and bottom plates and having their outer vertical edge portions in the same plane as said top and bottom plates, the inner vertical edge portions of said side plates being deflected laterally outwardly from said plane of the top and bottom plates. 140
6. In a sliding door of the type having a main portion of sheet metal having strengthening indentations therein, including vertically disposed corrugations adjacent the edges thereof; top and bottom reinforcing plates secured to the inner face of said main portion, said plates extending the full width of the door; vertically disposed, side reinforcing plates secured to the inner face of said main portion, said side plates extending between said top and bottom plates and having their outer vertical edge portions in the same plane as said top and bottom plates, the inner vertical edge portions of said side plates being deflected laterally outwardly from said plane of the top and bottom plates; and reinforcing bars along some of the edges of said door and secured to the outer side of said main portion. 150
7. In a railway car, horizontally slidably type metal door having a main portion comprised of a plurality of sheet metal panels secured together by overlapped joints and provided with integral, strengthening indentations therein disposed laterally outwardly from the original plane of the sheets; top and bottom sheet metal plates secured to the inner side of said main portion along the top and bottom edges thereof, said plates being adapted to bear against fixed portions of the car structure to function as guiding surfaces for the door during operation thereof; and vertically extending side sheet metal plates also secured to the inner side of said main portion along the front and rear vertical edges thereof, the attached inner vertical edge portions of said side plates being laterally outwardly offset with reference to the plane defined by said top and bottom plates, whereby said inner vertical edges of said side plates are prevented from fouling the fixed car parts during opening and closing of the door. 160
8. In a sliding door having a main portion comprised of sheet metal provided with top and bottom, outwardly disposed, horizontal corrugations incorporated therein; horizontally extending reinforcing plates secured on the inner side of said main portion and covering said top and bottom horizontal corrugations respectively; and vertically arranged reinforcing plates secured on the inner side of said main portion adjacent the vertical edges of the door and extending between said horizontal reinforcing plates, the inner edge portions of said vertical plates being laterally outwardly offset between said top and bottom plates. 170

bottom horizontal corrugations to at least the thickness of said vertical plates.

9. In a slidable door having a main portion comprised of sheet metal; horizontally extending top and bottom and vertically extending reinforcing plates secured to the inner side of said main portion adjacent the top, bottom and vertical side edges of the door, respectively, the extreme upper and lower ends of the vertical plates and 5 their outermost marginal portions lying in the same plane as the top and bottom horizontal reinforcing plates, the remaining portions of said vertical reinforcing plates and the central area of said main sheet metal portion being laterally

outwardly offset from said plane of the top and bottom reinforcing plates.

10. In a sliding door of the type having a main portion of sheet metal; strengthening sheet metal plates along all edges on the inner face of and secured to said main portion, the inner surfaces of the outer marginal portions of said plates lying in a common plane constituting the inside guiding plane of the door, portions nearest the center of the door of some of said plates and the corresponding adjacent areas of the main portion of the door being laterally outwardly offset from said inside guiding plane of the door. 80 85
